Term of patent 14 years

(Cl. D90—20)

Fig. 1

Fig. 3

Fig. 2

Fig. 1 is a perspective view of a tire showing my new design, it being understood that the tread portion shown is repeated throughout the circumference of the tire and that the sidewall configuration shown is repeated throughout the circumference, the opposite side of the tire being substantially like the side shown.

Fig. 2 is an enlarged fragmentary plan view of the tread portion of the tire shown in Fig. 1; and

Fig. 3 is an enlarged transverse sectional view through the tire taken substantially on the plane indicated by the line 3—3 of Fig. 2.

I claim:

The ornamental design for a tire, substantially as shown and described.
